UNITED STATES PATENT OFFICE.

GEORGE W. HYDE, OF ST. PAUL, NEBRASKA.

COMBINED WHIP-SOCKET AND REIN-HOLDER.

SPECIFICATION forming part of Letters Patent No. 618,680, dated January 31, 1899.

Application filed June 22, 1898. Serial No. 684,158. (No model.)

To all whom it may concern:

Be it known that I, GEORGE W. HYDE, of St. Paul, in the county of Howard and State of Nebraska, have invented a new and Improved Combined Whip-Socket and Rein-Holder, of which the following is a full, clear, and exact description.

The object of the invention is to provide a new and improved combined whip-socket and rein-holder which is simple and durable in construction, cheap to manufacture, and readily secured in place for conveniently and securely holding a whip and the reins for teams harnessed to buggies, lumber-wagons, and other vehicles.

The invention consists of novel features and parts and combinations of the same, as will be described hereinafter and then pointed out in the claims.

Reference is to be had to the accompanying drawings, forming a part of this specification, in which similar characters of reference indicate corresponding parts in all the figures.

Figure 1 is a sectional side elevation of the improvement as applied, the section being taken on the line 11 of Fig. 2. Fig. 2 is a sectional plan view of the same on the line 22 of Fig. 1. Fig. 3 is a face view of the clamp and gage-rests, and Fig. 4 is an edge view of one of the guideways.

The frame A for carrying the rein-holder and the whip-socket is made of spring metal in saddle form, the side members A' A² being adapted to straddle a support B for carrying the combined rein-holder and whip-socket. The connecting member A³ of the saddle-frame is adapted to rest on the top edge of the support, as is plainly indicated in Fig. 1. The lower member A² continues into a spring-loop C, from which rises a jaw D, arranged in front of and parallel to the member A², so as to form with the latter a pair of jaws for engaging and securely holding the reins. The upper end of the jaw D is bent forwardly into a ring E to permit of readily placing the reins between the jaws and also to prevent garments from being caught when a person passes over the device upon entering or leaving the vehicle on which the device is applied.

In order to regulate the tenacity of grip on the jaws and to form vertical guideways for

the jaws, I provide a clamp with guide-rests. (Shown in detail in Figs. 3 and 4.) The clamp G is made U-shaped, with the extreme ends 55 formed into points or prongs adapted to be driven into the support B, and the said clamp is adapted to rest on the outside of the jaw D and is provided at its ends with vertical wedge-shaped guideways G' for the side edges 60 of the jaw D. Bolts G² pass through the clamp G, guideways G', and the support B, so as to securely fasten the clamp in place after it has been adjusted. By adjusting the guideways G' up or down in the clamp G the space between the latter and the support B can be increased or diminished to give more or less spring action to the jaw D. Each of the guideways is preferably provided with a series of apertures for the bolt G² to engage one of them. It is understood that the clamp and guideways may be moved up or down on the two jaws to a desired position, and then the guideways are adjusted up or down in the clamp previous to driving the prongs into position on the support B.

The whip-socket forms an integral part of the member A' of the saddle-frame A and is formed by bending the lower end of the member A' outwardly to form a bottom H for the 80 socket, the outer end of said bottom continuing in the outer side H', provided at its side edges with bars H², bent inwardly to meet the member A' and complete the socket. Thus the member A² of the saddle-frame forms one 85 of the jaws for the rein-holder, while the member A' of said frame, as well as the jaw D, bottom H, outer side H', and bars H², are all formed of one single piece of spring sheet metal.

Having thus fully described my invention, I claim as new and desire to secure by Letters Patent—

1. A combined whip-socket and rein-holder, comprising a frame, a rein-holder having jaws, one of which is formed by one side of the saddle-frame, and a whip-socket having its inner side formed by the other side of the saddle-frame, substantially as shown and described.

2. A combined whip-socket and rein-holder, comprising a saddle-frame, a rein-holder having jaws, one of which is formed by one side of the saddle-frame, and a clamp and guide-

ways for the jaws and adapted to be secured to the support of the device, substantially as shown and described.

3. A combined whip-socket and rein-holder, comprising a saddle-frame, a rein-holder having jaws, one of which is formed by one side of the saddle-frame, and a clamp and wedge-shaped guideways for the jaws and adapted to be secured to the support of the device, the
- 5 said clamp being made U-shaped to extend over the front face of the outer jaw, and the guideways being held adjustably on the clamp to engage the side edges of the jaws, substantially as shown and described.

4. A combined whip-socket and rein-holder, 15 comprising a frame, a rein-holder having jaws, one of which is formed by one side of the saddle-frame, a whip-socket having its inner side formed by the other side of the saddle-frame, one side of the whip-socket being provided 20 with spaced integral bars bent over to meet the inner side of the socket, substantially as shown and described.

GEORGE W. HYDE.
